ADVERTISING DISPLAY BOARD

Wray Parks Pearman, Chevy Chase, Md., assignor to Wiz Novelty Corporation, New York, N. Y.

Application February 6, 1948, Serial No. 144,327

Term of patent 3½ years

(Cl. D1—2)

To all whom it may concern:

Be it known that I, Wray Parks Pearman, a citizen of the United States, residing at Chevy Chase, in the county of Montgomery and State of Maryland, have invented a new, original, and ornamental Design for an Advertising Display Board, of which the following is a specification, reference being had to the accompanying drawing, forming part thereof, in which:

The single figure is a face view of the advertising display board, showing my new design; the board is of no appreciable thickness.

I claim:

The ornamental design for an advertising display board, as shown and described.

WRAY PARKS PEARMAN.
